UNITED STATES PATENT OFFICE.

BICKNELL HALL, OF TAUNTON, ASSIGNOR TO THE WAINWRIGHT MANUFACTURING COMPANY OF MASSACHUSETTS, OF BOSTON, MASSACHUSETTS.

TOOL FOR USE IN CORRUGATING-MACHINES.

SPECIFICATION forming part of Letters Patent No. 541,852, dated July 2, 1895.

Application filed January 4, 1895. Serial No. 533,877. (No model.)

To all whom it may concern:

Be it known that I, BICKNELL HALL, of Taunton, in the county of Bristol and State of Massachusetts, have invented a new and useful Improvement in Tools for Use in Corrugating-Machines, of which the following is a specification.

My improvement relates particularly to such tools as are used in the corrugation of tubes.

It is common in machines for corrugating tubes to use a rotary tool which, bearing with considerable pressure upon the tube, causes the indentation of the tube, and as the tube is rotated, or as the tool holder carries the tools about the tube, the indentation is continued about the periphery of the tube, so that it forms either an annular or spiral corrugation. Such tools and the machines in which they are used are now well known in the art, but where the tool has a spiral projection or thread about its periphery for the purpose of causing the indentation, it is sometimes very essential that a certain point on the periphery of the tool shall first strike the surface of the tube and cause the beginning of the corrugation. Hitherto, so far as I am aware, no especial means have been employed to bring about this result with certainty and accuracy.

My invention will be understood by reference to the drawings, in which—

Figure 1 illustrates in elevation the best form of my invention now known to me, Fig. 2 being an end view.

A is the tool holder which may be of any ordinary construction. As shown, it is an ordinary forked holder and in the ends a, a' of the fork is journaled a shaft B carrying the tool C which is keyed thereto, so that the shaft will turn whenever the tool turns. One end of the shaft projects beyond one of the forks a' and a weight D is attached to it. The most convenient form of weight is that shown in the drawings, it being so constructed that

gravity will always bring it to the position shown, when the tool is free. Being attached to the shaft B by set screw d , it may be adjusted about the shaft so as to alter its relation to any particular point on the periphery of the tool.

My tool is used in a corrugating machine as such tools are ordinarily used, but whenever the tube is removed, the weight D in assuming the position shown in the drawings, will always bring the tool to a particular position, so that when the next tube is put into the machine to be corrugated, a particular point on this tool will begin the corrugation of the tube, and by adjusting the position of the weight, the first point of contact can be determined.

This invention has been found of great value because, more particularly in making an annular corrugation upon a tube, it is essential that a certain portion of the tool act first to begin the corrugation.

This device is the first which regulates or adjusts the position of the tool in its first contact with the tube, so far as I now know, and being automatic in its operation, is the simplest way, as it now seems to me, for causing the desired result.

What I claim as my invention is—

1. The corrugating tool above described, in combination with means whereby when not in use, its position about its axis will be automatically adjusted to a uniform position, as and for the purposes set forth.

2. In combination with a corrugating tool and its shaft, the weight D adjustably mounted on said shaft, as and for the purposes set forth.

In testimony whereof I have hereunto set my hand this 15th day of November, 1894.

BICKNELL HALL.
